Primary Examiner — Susan Bennett Hattan*Assistant Examiner* — Janice Hallmark(74) *Attorney, Agent, or Firm* — Hankin Patent Law APC; Jimmy Sauz; Kevin Schraven(57) **CLAIM**

The ornamental design for an e-liquid bottle, as shown and described.

DESCRIPTION

FIG. 1 is a top perspective view of an e-liquid bottle, showing our new design.

FIG. 2 is a bottom perspective view thereof.

FIG. 3 is a front elevational view thereof.

FIG. 4 is a rear elevational view thereof.

FIG. 5 is a left side elevational view thereof.

FIG. 6 is a right side elevational view thereof.

FIG. 7 is a top plan view thereof; and,

FIG. 8 is a bottom plan view thereof.

The broken lines in the drawings depict parts of the e-liquid bottle that form no part of the claimed design.
